Harry L. Duncan

UNITED STATES PATENT OFFICE.

HARRY L. DUNCAN, OF MAHWAH, NEW JERSEY.

ACOUSTIC DIAPHRAGM.

Application filed March 31, 1919. Serial No. 286,351.

To all whom it may concern:

Be it known that I, HARRY L. DUNCAN, a citizen of the United States, and resident of Mahwah, county of Bergen, State of New Jersey, have made a certain new and useful Invention Relating to Acoustic Diaphragms, of which the following is a specification, taken in connection with the accompanying drawing.

- 10 This invention relates especially to acoustic diaphragms for phonographs, telephones and other purposes in which the metallic or other diaphragm is formed with a wavy or fluted edge so that the edge may be given a definite degree of peripheral elongation. The diaphragm may be clamped or mounted in such a way that this irregular or fluted edge is forced more or less into the flat or straight position so that in this way the edge 15 20 diameter of the diaphragm tends to enlarge which automatically places the central portions of the diaphragm under radial tension and increases the pitch or efficiency of the diaphragm for many purposes. In the 25 case of metal diaphragms the central portion of the diaphragm may in many cases be advantageously stiffened by being coned up or corrugated at the same time that the edge portion of the diaphragm is given a fluted or wavy shape in suitable dies or other 30 forming tools, and if desired, an edge tensioning ring or member of suitable wavy or fluted form may in some cases be advantageously more or less enclosed within or 35 united to the edge portion of the diaphragm and sufficiently flattened in the mounting or subsequent use of the diaphragm so as to place the portions of the diaphragm within under suitable radial tension. Such diaphragms may be made of any suitable material and steel or other sheet metal such as 40 brass, bronze or aluminum alloys may be used in some cases or plastic or mouldable material may be used for this purpose, such as celluloid or rubber with or without such 45 united or enclosed metal tensioning members, or fibrous materials may be used in many cases, and also paper, paper pulp or cloth which may in some cases be advantageously impregnated or coated with cementing material of various kinds, such, for example, as phenolic condensation compositions like bakelite varnish which under the heat curing treatment stiffen the fabric or

fibrous material and tend to maintain its 55 shape.

In the accompanying drawings showing in a somewhat diagrammatic way various illustrative embodiments of this invention,

Fig. 1 is a central section through a dia- 60 phragm during the making thereof.

Fig. 2 is a similar view showing the dia- phragm mounted.

Figs. 3 and 4 are similar sectional views 65 showing other forms of diaphragm.

Fig. 5 is a sectional view showing the edge drawing or fluting of a metallic diaphragm; and

Fig. 6 shows the diaphragm which may 70 be produced in this way.

Many types of acoustic diaphragms may advantageously be provided with fluted or sinusoidal edge tensioning members formed integral with or secured to the diaphragm so as to have a substantially definite degree 75 of extra peripheral elongation. When the diaphragms are mounted for use or prior thereto, this edge tensioning member may be more or less flattened or straightened so as to have sufficient increased diameter to 80 exert a valuable radial tensioning action on the inner portions of the diaphragm which may either be substantially flat or given any other desired or suitable shape as by stiffening corrugations or projections in some cases. The edge tensioning device naturally has such strength and size as is suited to the size of the diaphragm and for special large diaphragms of six inches or more 85 in diameter heavier edge tensioning mem- 90 bers are naturally necessary to properly ten- sion the heavier and thicker diaphragms used under such conditions. In large dia- phragms it is usually desirable to have a greater number of edge flutes or waves to 95 accommodate the added peripheral length of the tensioning member before it has exerted its tensioning action. For small dia- phragms, such as are more generally used for phonograph and similar purposes and 100 where the diaphragm is only two or three inches or so in diameter, thinner and lighter material is usually desirable for the dia- phragm body, and where sheet steel is used for this purpose it may advantageously be 105 given a more uniform structure and elas- ticity in different directions by special roll- ing or preliminary treatment, including

cross-rolling of the plates. The steel should of course have as uniform thickness as possible and a good light diaphragm of this character may be three to ten thousandths of an inch or so thick and have such composition as is suited to the particular use of the diaphragm, depending, of course, on whether it is to have magnetic properties or not. In some cases it is advantageous to have the diaphragm center stiffened so as to get more uniform action in connection with the operating mechanism connected therewith and as indicated in Fig. 1 the diaphragm 1 of such sheet metal, for instance, may have its center 3 coned or dished up in such form as to give suitable stiffness at the same time that the edge portions of the diaphragm are given a fluted or wavy form in the stamping or shaping devices. For many purposes it is desirable to simultaneously force together the diaphragm and edge tensioning member which may be used therewith in some cases, and an edge tensioning ring which is of considerably thicker sheet metal than the diaphragm is shown in Fig. 1 and may have four to six times as great thickness as the diaphragm and may have a radial width much greater than its thickness, as is indicated. Ample radial strength and stiffness may thus be secured combined with the facility of bending transversely to the plane of the diaphragm in fluting or straightening the ring. It is sometimes desirable to have the tensioning ring or member 6 arranged in the stamping die when the diaphragm is shaped up and its edge fluted with or without coning or stiffening of the center portion and in such case the diaphragm edge may be flanged down around the tensioning ring so as to form a flange 4, a subsequent spinning or shaping operation being resorted to if desired to force the extreme edge 5 of this diaphragm around the other side of the stiffening ring which is thus more or less enclosed by the diaphragm edge. The part 2 of the diaphragm edge is shown as somewhat separated from the tensioning ring 6 for greater clearness, although it is of course understood that these parts will be forced closely and tightly together at the same time that the diaphragm edge and tensioning ring are fluted or corrugated to the desired extent which for small diaphragms may mean a difference of a sixteenth to an eighth of an inch or so between the planes of the high points, such as 2, and the low points, such as 12, of the diaphragm edge which may have four to six or more flutes therein. With metal diaphragms it is usually desirable to definitely secure the diaphragm edge to any tensioning ring or member that may be used, and for this purpose the diaphragm edge and tensioning ring may be soldered, welded or otherwise united while

still in their fluted or wavy form and for this purpose they may be clamped together in any desired way after the tensioning member and flat or other diaphragm have been edge fluted and in some cases annealed to relieve local stresses and then spot welded at suitable intervals or soldered together by various soldering compositions depending on the materials used.

Such a diaphragm may be mounted in a clamping support such as is indicated diagrammatically in Fig. 2 as comprising two clamping members or rings 9, 10 between which the edge portions of the diaphragm may be clamped, suitable washers or cushioning members such as 8 of yielding material being preferably interposed, and for this purpose relatively soft fibrous material, such as soft paper or rubber sheeting or the like, may be employed and having sufficient thickness so that the diaphragm edge is firmly engaged throughout its entire periphery by these clamping or supporting washers. The clamping members are preferably brought together to such an extent as to straighten the wavy or fluted edge portion of the diaphragm sufficiently to secure the radial tensioning desired in the diaphragm body and a considerable increase of pitch can be secured in this way as well as more definite and desirable results for many classes of acoustic work.

Fig. 3 shows a form of diaphragm which may, if desired, be made of substantially uniform thickness throughout the edge portions and adjacent inner portions of the diaphragm, the desired fluted or wavy character of the diaphragm edge being secured by any suitable method depending on the diaphragm material employed. A thin sheet metal diaphragm 1 may be stamped or forced into the desired shape at the same time that the diaphragm center 3 is forced out into more or less conical projecting position which stiffens this part of the diaphragm. The edge portions 14, 15 may be given a fluted or wavy character and may have a half a dozen or more edge flutes such as 14, 15 in which there is a difference of a sixteenth of an inch more or less between the planes of the high and low points in small diaphragms a couple of inches in diameter, this amount of edge fluting depending somewhat on the intended uses of the diaphragm. If desired, however, a diaphragm of this general character with or without corrugated or conically reinforced center portions may in many cases be made of celluloid or various rubber compositions, the degree of edge fluting and the thickness of the diaphragm at various points being of course regulated by the characteristics of the material employed in each case as well as the uses for which it is intended. A desirable material for many forms of dia-

phragm is cloth or other fibrous material coated and preferably more or less thoroughly impregnated with phenolic condensation cementing compositions such as bakelite, redmanol or condensite varnish, several sheets of soft thin and strong paper or fine textured cotton or other cloth being desirable. Several sheets of thin muslin or other cotton fabric which has been thoroughly 5 impregnated with bakelite varnish or similar phenolic condensation cementing material and dried may be cut approximately to size and then assembled in a heated mold which can readily heat the material to a 10 sufficient extent to render it soft and pliable after which it may be shaped under high pressure and at the proper curing heat for the cementing material employed which for such bakelite compositions is approximately 15 300° to 320° Fahrenheit or so for a curing time of ten or twenty minutes. When such material is united at the high pressure of a number of hundred pounds per square inch the different layers are permanently united 20 by the incorporated cured cementing material so that the cured diaphragm substantially retains the shape given to it during the molding operation and in this way a fluted or wavy tensioning edge may be def- 25 initely formed of such character that when partially flattened between rubber or other yielding clamping members a desirable tension may be given to the central part of the diaphragm which may in some cases be si- 30 multaneously formed into reenforced pro- jecting position during the molding opera- 35 tion. Fig. 4 shows another form of dia- phragm may be made of such material and may have four to six or more edge flutes or 40 wavy portions, such as 14, 15, connected with a suitably reenforced or stiffened dia- phragm center of any desired character. If desired, such a stiffened center may com- 45 prise a series of corrugations 17, 18, 19, the center 16 being flat if desired and stiffened in other ways under some conditions. The Fig. 4 diaphragm may, however, be formed of steel or other metal in many cases and the flat diaphragm center 16 may under these 50 conditions be advantageous for cooperation with magnetic actuating or other members which do not need to be given special shape in order to cooperate properly therewith.

In some cases the edge flutes or peripheral 55 elongation of a diaphragm may be formed in other ways, as for instance, by edge drawing rolls such as are diagrammatically in- 60 dicated in Fig. 5. The two sets of rolls of this character, such as 22, 23, may be ar- 65 ranged on shafts 24 and one or both sets positively rotated so that a sheetmetal dia- phragm 20 arranged between these three or four pairs of conical fluting rolls may be subjected to a compressing and drawing operation at each pass between the rolls so

that its peripheral portion may be drawn out or elongated to the desired extent as determined by the length of this rolling treatment and the pressure and conditions there- 70 of. The diaphragm 20 after such an edge rolling or fluting treatment is preferably stamped in suitable dies to give more def- 75 inite shape to the edge flutes 21, 25, which may thereafter be employed for tensioning the inner portions of the diaphragm by 75 clamping them between relatively flat clamp- 80 ing or supporting surfaces. This flattens the fluted or wavy edge portions sufficiently so that they can exert a desirable tension- 85 ing action on the central portions of the dia- phragm which is of greater efficiency be- 90 cause of the hardening and strengthening of the metal during the edge fluting rolling operation to which it has been subjected.

This invention has been disclosed in con- 85 nection with a number of illustrative em- bodiments, forms, proportions, elements, parts, shapes, materials, compositions, con- 90 ditions, and methods of preparation, pro- duction and use, to the details of which dis- 95 closure the invention is not of course to be limited, since what is claimed as new and what is desired to be secured by Letters Patent is set forth in the appended claims:

1. The acoustic diaphragm having a stiff- 95 fened center and edge portions, and a me- tallic fluted edge tensioning ring having four to six flutes to secure increased peripheral elongation and enclosed by and secured to 100 the edge portion of said diaphragm, so that said tensioning ring may be flattened in the diaphragm supporting devices to radially tension the inner central portions of the dia- phragm.

2. The acoustic diaphragm having a metal- 105 lic fluted edge tensioning ring enclosed by and secured to the edge portion of said dia- phragm, so that said tensioning ring may be flattened to radially tension the inner central 110 portions of the diaphragm.

3. The acoustic diaphragm having a me- tallic fluted edge tensioning ring secured to 115 the edge portion of said diaphragm and adapted to have its fluted portions flattened to radially tension the inner central portions of the diaphragm.

4. The acoustic diaphragm having a flat sectioned metallic edge tensioning member having three or more flutes and enclosed 120 within and secured to the edge portion of said diaphragm and adapted to be flattened in the diaphragm supporting devices to ra- dially tension the inner central portions of the diaphragm.

5. The acoustic diaphragm having a wavy 125 tensioning member secured to the outer por- tion of said diaphragm and adapted to be flattened in the diaphragm supporting de- vices to radially tension the inner portions of 130 the diaphragm.

6. The acoustic diaphragm comprising a stiffened center and edge portions having a fluted form to secure substantially definite increased peripheral elongation and adapted 5 to be flattened in the diaphragm supporting devices to radially tension the inner portions of the diaphragm.
7. The acoustic diaphragm comprising outer portions having a wavy form to secure 10 substantially definite increased elongation and adapted to be flattened to radially tension inner portions of the diaphragm.
8. The acoustic diaphragm comprising outer portions which have been flattened from a fluted form comprising three or more 15 flutes to impart substantially definite radical tension to inner portions of the diaphragm.
9. The acoustic diaphragm comprising outer portions which have been distorted from a substantially definite wavy form to 20 impart radial tension to inner portions of the diaphragm.
10. The acoustic diaphragm having a flattened wavy tensioning member secured to the outer portion of said diaphragm and imparting radial tension to inner portions of the diaphragm. 25

HARRY L. DUNCAN.
